HERSCHEL C. PARKER, OF NEW YORK, N. Y., ASSIGNOR TO PARKER-CLARK ELECTRIC COMPANY, OF JERSEY CITY, NEW JERSEY, A CORPORATION OF NEW JERSEY.

INCANDESCENT ELECTRIC LAMP.

No. 821,056.

Specification of Letters Patent.

Patented May 22, 1906.

Application filed April 21, 1904. Serial No. 204,170.

To all whom it may concern:

Be it known that I, HERSCHEL C. PARKER, of New York, in the county of Kings and State of New York, have invented a new and 5 Improved Incandescent Electric Lamp, of which the following is a full, clear, and exact description.

My invention relates to improvements in incandescent electric lamps; and the object 10 of my invention is to produce a cheap and simple lamp which is very durable and which consists in the main of a pencil formed chiefly of refractory non-conducting substance, but with a small percentage of conductive sub- 15 stance mixed therewith, the whole being ar- ranged and combined so that a current will pass through the pencil when the latter is cold and will quickly raise the same to a bright incandescence.

20 I have found by experiments that by min- gling some refractory non-conductive sub- stance, such as thorium oxide or carborundum, with a small percentage of a refractory con- ductor, such as graphite, and shaping the 25 mass into a pencil, the latter being prefer- ably compressed, I can cause a current to pass through the pencil when the latter is cold, and it will still have sufficient resist- 30 ance to cause the pencil to be raised to a high heat, and thus an efficient lamp is provided. It is probable that other substances than the 35 thorium oxide and carborundum may be used; but the substances must be of such a nature that when mixed with the conductor they will produce a light-giving pencil and not one which will merely glow under the influence of the current.

With these ends in view my invention con- 40 sists of an electric lamp, the construction of which will be hereinafter described and claimed.

Reference is to be had to the accompan- 45 ying drawings, forming a part of this specifi- cation, in which similar figures of reference in- dicate corresponding parts in both views.

Figure 1 is a detail elevation, with the 50 terminals in section, of the simplest form of the lamp. Fig. 2 is a longitudinal section, with the pencil in elevation, of the lamp provided 55 with an inclosing transparent or translucent cylinder.

The principal portion of my lamp consists of the pencil 10 and its conducting-terminals 11. The pencil 10 is made, as above re- 55 marked, preferably of thorium oxide or car- borundum mixed with some good refractory conductor. To get the best results, there should be approximately three or four parts of the oxid to one of the conductor, and for the latter graphite works perfectly. To 60 form the pencil, the ingredients are reduced to a fine powder and thoroughly mingled and the parts may be held together by a suit- 65 able binder forming a sort of dough which can be forced through a die to make the pen- cil of the right size and the pencil can be cut into the requisite lengths and dried and baked. As a result I produce a pencil which will conduct the current when cold, thus ob- 70 viating the necessity of providing a prelimi- 75 nary heating, and at the same time the pen- cil is of comparatively high resistance and of such a nature that it will not flame, but will glow with a bright incandescence when sealed within a tube from which the air is partially exhausted.

The terminals 11 are preferably of graphite and receive the leading-in wires 12, the terminals being also arranged so as to fit snugly like stoppers in a transparent or translucent 80 tube 13, which is preferably of glass, as the air-gap between the tube and the pencil 10 is sufficient to prevent the glass from slag- 85 ging. The graphite 11 is held in place by a suitable cement or seal, as 14. The air can 90 be exhausted from the tube in any usual way, and this can be done easily by leaving a vent in the glass, heating the pencil to incandes- 95 cence, thus expelling the air and gases and sealing the vent while the pencil is still hot.

I do not wish to limit the invention to the use of the ingredients named, as other stable oxides or refractory materials can be substi- 95 tuted for the said ingredients; but they must be of such a nature that a firm hard pencil can be formed and also of such a nature that the constituents will not unite chemically at the temperature of incandescence or disinte- 95 grate at the same temperature.

It will be understood that the terminals 11 100 may be independent blocks of graphite, as shown, or the pencil 10 can have enlarged

ends corresponding in shape to the parts 11, so as to fill the tube 13 near the ends, the result being the same in either case—in other words, the parts 10 and 11 forming really the body portion of the lamp.

Having thus fully described my invention, I claim as new and desire to secure by Letters Patent—

1. An incandescent electric lamp comprising a transparent tube, a pencil of mingled refractory conducting and non-conducting materials held longitudinally in the tube, and terminals of larger cross-section than the pencil, said terminals filling the tube ends and forming a support for the pencil so as to make

a gap between the pencil and the sides of the tube.

2. An incandescent electric lamp comprising a transparent tube, a pencil of mingled refractory conducting and non-conducting materials arranged longitudinally in the tube so as to leave a gap between itself and the tube end, terminals for the pencil, said terminals filling and closing the tube, and a seal for the ends of the tube. 20
